UNITED STATES PATENT OFFICE.

WILLIAM NEVILLE, OF DULUTH, MINNESOTA.

GASOLENE-EVAPORATOR.

1,226,107.

Specification of Letters Patent.

Patented May 15, 1917.

Application filed October 23, 1915. Serial No. 57,562.

To all whom it may concern:

Be it known that I, WILLIAM NEVILLE, a citizen of the United States of America, residing at Duluth, in the county of St.

5 Louis and State of Minnesota, have invented certain new and useful Improvements in Gasolene-Evaporators, of which the following is a specification, reference being had therein to the accompanying drawing.

10 This invention relates to gasolene evaporators and has for its principal object the production of a simple and efficient means for heating the gasolene before the same is conducted to the carburetor of an explosive engine.

15 Another object of this invention is the production of a gasolene evaporator which comprises a casing so constructed as to allow the device to be conveniently supported upon the exhaust pipe of an engine whereby the gasolene circulating therethrough may be heated before being conducted to the carburetor of an explosive engine.

20 25 A still further object of this invention is the production of a gasolene evaporator having a casing provided with an inner chamber, this casing being adapted to allow the water from the engine to pass around the inner chamber so as to heat the gasolene circulating therethrough, this water also being heated since the device is supported upon the exhaust pipe of the engine.

30 35 With these and other objects in view, this invention consists of certain novel combinations, constructions, and arrangements of parts as will be hereinafter fully described and claimed.

40 In the accompanying drawings:—

Figure 1 is a side elevation of the gasolene evaporator, illustrating the manner in which the invention is used.

Fig. 2 is a detailed perspective view of the gasolene evaporator.

Fig. 3 is a longitudinal vertical section through the invention.

Fig. 4 is a section taken on line 4—4 of Fig. 3, looking in the direction of the arrows.

Fig. 5 is a central transverse section through the device.

Fig. 6 is a fragmentary top plan view of a portion of the outer casing, illustrating one of the ears used for attaching the same.

55 Referring to the accompanying drawings by numerals it will be seen that the gaso-

lene evaporator comprises an outer casing 1 and an inner chamber 2. This outer casing 1 comprises a base portion 3 having the inwardly bulged portion 4 which is so constructed as to rest snugly upon the exhaust pipe 5 of the engine 6. The side walls 7 and end walls 8 are formed integral so as to support the integral top 9. The ears 10 are formed integral upon the top 9 so as to be positioned in alinement with each other and are provided with openings 11. The U-bolt 12 passes around the exhaust pipe 5 so as to pass through the openings 11 formed in the ears 10, as clearly shown in Fig. 5. The retaining nuts 13 may then be threaded upon the threaded ends 14 of the bolt 12 for firmly mounting the evaporator in its correct position upon the exhaust pipe 5.

70 The inner chamber 2 is fixedly carried at a spaced distance from the inner portions of the outer casing 1 by means of the necks 15 which are formed integral upon the casing 1 and chamber 2 as clearly shown in Fig. 3. Vertically threaded openings 16 extend through these necks 15 for allowing the fuel pipes 17 to be connected therewith for supplying and relieving the chamber 2 of the gasolene or other liquid fuel. The chamber 2 is also supported at its end portions by the cores 18 which are integrally formed upon the inner surfaces of the end walls 8 and the ends of the chamber 2.

75 It will also be noted that the side walls 7 are provided with internally threaded openings 19 communicating with the interior of the casing 1. The water pipes 20 may be threaded into these openings conveying water into the casing and also relieving the casing, thereby maintaining a circulation of water through the casing.

80 85 90 95 When this device is in use it is first mounted upon the exhaust pipe 5 and then the U-shaped bolt is passed around the exhaust pipe so as to extend through the openings in the ears, at which time the nuts are threaded into their correct positions for retaining the casing in its correct position upon the exhaust pipe. The water pipes 20 are then threaded into the openings 19 and these water pipes are connected to the engine. It is of course obvious that these water pipes may be connected with other elements, such for instance as a carburetor when the same is provided with a water-jacket, and will operate as efficiently under all conditions. The pipes 17 are then threaded.

ed into the necks 15 so as to allow one pipe to extend from the fuel tank while the other pipe extends to communicate with the carbureter. It will be seen that as the heated 5 water from the engine passes into the casing through one of the pipes 20 and then circulates about the inner chamber, it will heat the inner chamber. The water may then 10 continue to pass out through the other pipe 20, thereby maintaining a circulation about the inner chamber. The heat of this water may be greatly increased by the exhaust pipe 5 which bears against the bulged portion 4 of the base 3. This additional heat 15 will also heat the water circulating about the chamber whereby the gasoline passing through the inner chamber 2 will be heated to a high degree.

From the foregoing description it will be 20 seen that a very simple and efficient gasoline evaporator has been produced in which the device is provided with a simple and efficient means for firmly supporting the same upon the exhaust pipe of the explosive engine, and which is provided with an inner chamber fixedly supported at distances from the inner surfaces of the casing whereby water may be freely circulated around this inner chamber for heating the gasoline passing therethrough to a very high degree and thereby cause the engine to have a greater power and reduce the cost of operating the engine, since the inner chamber will heat the gasoline passing therethrough so as to assist 30 in the evaporation thereof before the gasoline or other fuel is conducted to the carbureter. It will further be seen that the outer casing 1 is constructed so as to allow the openings 22 to extend through the cores 18 at the end portions thereof. These openings are internally threaded, if so desired, and are adapted to be used when the evaporator is being constructed. When being 40 constructed any suitable supporting means 45 may be passed through these openings 22 so as to engage the end portions of the inner casing for supporting the same. The gas which is created by the construction of a metallic device of this character may also escape through these openings, while these 50 openings also provide sufficient space for the removal of the foundry sand after the metal has hardened. After the device has been completed these openings 22 may be permanently closed by the externally threaded 55 plugs 21, as clearly shown in Fig. 3, or by driving the plugs as desired, as these openings will not be of any more use as their 60 functions will have been accomplished.

It is also obvious that this evaporator may be made of any metal desired, inasmuch as

the constructing thereof of one metal or another will not depart from the spirit of this invention as presented by the claims.

What I claim is:

1. In a gasoline evaporator, the combination of a casing, said casing having a base provided with an inwardly bulged portion, said bulged portion being adapted to fit snugly upon the exhaust pipe of an engine, 70 means for retaining said casing in its correct position, said casing being adapted to be supplied with water whereby the heat from the exhaust pipe will heat the water, said casing provided with an internal chamber 75 and means whereby gasoline may pass through said chamber so as to be heated by the water carried within said casing.

2. In a gasoline evaporator, the combination of an outer casing, said casing provided 80 with a base having an inwardly bulged portion, integral ears extending from the upper portions of said casing, a U-bolt carried by said ears, said bulged portion being adapted to fit upon the exhaust pipe of an engine so 85 as to allow said U-bolt to embrace the exhaust pipe for securely retaining the casing in its correct position upon the exhaust pipe, a chamber carried within said casing and fixedly secured at spaced distances from the 90 side portions thereof, means for supplying said casing with water, means for supplying said chamber with gasoline, whereby the heat from the exhaust pipe will heat the water within the casing for heating said 95 chamber, thereby heating the gasoline passing through said chamber to a high degree.

3. In a gasoline evaporator, the combination of a casing, said casing being adapted to be mounted upon an exhaust pipe of an 100 explosive engine, a chamber positioned within said casing, integral necks connecting the upper portions of said chamber to the upper portions of said casing, said necks provided with vertically internally threaded openings, 105 pipes carried within said openings and communicating with the interior of said chamber whereby gasoline may be conducted to and conveyed from said chamber, said casing provided with openings in its side portions, 110 pipes threaded into said openings for conveying water to and from said casing, whereby the water within the casing may be heated by the exhaust pipe upon which the casing is mounted so that as the water circulates about said chamber it will be heated 115 so as to impart heat to said chamber, whereby the gasoline passing through said chamber may be heated to a high degree.

In testimony whereof I hereunto affix my 120 signature.

WILLIAM NEVILLE.
